UNITED STATES PATENT OFFICE.

GEORGE E. GRIMM, OF TOLEDO, OHIO, ASSIGNOR TO THE WILLYS-OVERLAND COMPANY, OF TOLEDO, OHIO, A CORPORATION OF OHIO.

COWL VENTILATOR.

Application filed July 27, 1922. Serial No. 577,867.

This invention relates to an automobile body structure and particularly to the ventilation of the same. It is an object of my invention to provide a ventilator, preferably located in the cowl, and operable from within the automobile, which shall be simple, efficient and inexpensive to manufacture. A further object is to provide in such a ventilator for the deflection of air inward into the cowl as well as for the concealment of the operating mechanism when the ventilator is open.

Other objects relating to details of construction and economies of manufacture will be apparent as I proceed with the detailed description of an embodiment of the invention illustrated in the accompanying drawing in which:

Figure I is a top plan view of a portion of the cowl and instrument board, with parts broken away to more clearly show my invention applied thereto.

Fig. II is a longitudinal cross sectional view taken on the line II-II of Fig. I and

Fig. III is a transverse sectional view taken on the line III-III of Fig. I.

The same reference numbers refer to the same parts throughout the views.

Referring to the drawing, the cowl 5 connecting with the instrument board 6 has a ventilating opening 7 therein, the cowl at the edge of the opening being turned up to form a flange 8. A cover 9, shown curved to conform to the curvature of the cowl, fits over the flanged opening 7 and has strips of packing 10, such as felt, held in place by an inner plate 11 suitably secured to and forming a part of the cover.

A member 12 having the combined function of a support for the cover and a deflector of the air entering the cowl comprises a sheet metal plate having flanges 13 and 14 at one side for attachment to the cover and end flanges 15, each of which has an extension or lug 16, by which the cover is pivotally mounted. Opposite each end of the plate member 12 is an angle bracket 17 secured to the under side of the cowl and carrying a shaft 18 upon which the member 12 is journalled at the lugs or extensions 16. The plate member 12 has a portion of its side edge opposite the flanges 13 and 14 cut away as at 19 and adjacent opposite sides of this cut away portion two angle brackets

20 are mounted which form bearings for trunnions formed on the opposite ends of a cylindrical nut member 21. An operating rod 22 is threaded transversely through this nut member and is of sufficient length to reach through the instrument board 6, where it has a bearing in a member 23 and terminates in a milled hand wheel 24. The rod is held from outward movement by a washer 25 and a pin 26 as shown in Fig. II, while its inward movement is restricted by a coil spring 27 housed in a counter bore in the member 23 and engaging the hand wheel 24. In order to eliminate rattling of the cooperating parts, a wire spring 28 is used which engages the cover, the shaft and the nut. In the form illustrated, this spring has a loop portion engaging the adjacent felt strip 10, an intermediate portion encircling the shaft 18 and opposite end portions engaging the nut 21.

When the hand wheel 24 is turned in one direction the cowl is swung about the shaft 18 to a raised position, and in this position the plate 12 serves to direct the air inward through the cowl opening. By reason of the fact that the shaft, the nut, the threaded end of the operating rod and the spring 28 are all located above and to the rear of the plate 12, they are effectively hidden from view when the cover is in its raised position.

While I have shown and described in detail a particular structural embodiment as illustrative of my invention, I do not wish to be limited thereby, since various changes might be made therein without departing from the scope of the invention covered by the appended claims.

Having thus described my invention, what I claim as new and desire to secure by Letters Patent, is:

1. In an automobile, a cowl having a ventilating opening therein, a cover therefor, a member secured to said cover and extending into said cowl, a shaft pivotally connecting said member to said cowl, a nut pivotally carried by said member, operating means engaging said nut and a spring engaging said cover, said shaft and said nut.

2. In an automobile, a cowl having a ventilating opening therein and a flange surrounding said opening, a cover for said opening, a member secured to said cover and extending into said cowl, a shaft pivotally con-

- necting said member with said cowl, a nut pivotally connected to said member, an operating rod threaded into said nut, and a spring engaging said cover, said shaft and 5 said nut.
3. In an automobile, a cover for a ventilating opening, having an arm, means for pivotally mounting said arm, a pair of lugs on said arm, a nut having trunnions mounted 10 in said lugs, and a wire spring coiled about said means and having its opposite ends engaging respectively said cover and said nut.
4. In an automobile body, a cowl having a ventilating opening, a cover therefor, a 15 plate rigidly secured to the cover and extending longitudinally thereof and downwardly and rearwardly beneath the same, means at opposite ends of the plate for pivotally supporting it beneath the cowl, and 20 means operatively connected with the plate for opening and closing the cover.
5. In an automobile body, a cowl having a ventilating opening, a cover therefor, a plate substantially the length of the opening, said plate being rigidly secured to the cover and extending longitudinally thereof and downwardly beneath the same, a member rotatably mounted upon the plate, and an operating member for the cover having 25 screw-threaded engagement with said rotatably mounted member.
6. In an automobile body, a cowl having a ventilating opening, a cover therefor, a plate rigidly secured to the underside of the cover 30 and extending longitudinally thereof and downwardly beneath the same, means pivotally supporting the plate beneath the cowl, and operating means for the cover pivotally connected with the plate.
7. In an automobile body, a cowl having a ventilating opening, a cover therefor, a plate rigidly secured to the underside of the cover and extending longitudinally thereof and downwardly beneath the same, means 35 pivotally supporting the plate beneath the cowl, a member rotatably mounted upon the plate, and operating means for the cover connected with said rotatably mounted member and adapted to effect the raising and 40 lowering of the cover.
8. In an automobile body, a cowl having a ventilating opening, a cover therefor, a plate rigidly secured to the underside of the cover and extending longitudinally thereof and downwardly beneath the same, means 45 for pivotally supporting the plate at its opposite ends beneath the cowl, operating means for the cover pivotally connected with 50 the plate, and means yieldingly engaging the cover to prevent rattling of the same. 60
9. In an automobile body, a cowl having a ventilating opening, a cover therefor, a downwardly extending arm rigidly secured to the cover intermediate its sides, means for pivotally supporting the arm beneath the 65 cowl, a member rotatably mounted upon the arm beneath the pivots thereof, and an operating rod for the cover having screw-threaded engagement with said member. 70
10. In an automobile body, a cowl having a ventilating opening, a cover therefor, a plate secured to the cover and extending downwardly beneath the same, said plate having angular end portions, means connected with said end portions for pivotally supporting the plate beneath the cowl, and operating means for the cover pivotally connected with said plate. 75
11. In an automobile body, a cowl having a ventilating opening, a cover therefor, a 80 downwardly extending plate secured to the cover beneath the same, said plate having angular end portions formed thereon, means connected with said end portions for pivotally supporting the plate beneath the cowl, 85 bearings connected with said plate, a member having trunnions journaled in said bearings, and means connected with said member for moving the cover to and from closed position. 90
12. In an automobile body, a cowl having a ventilating opening, a cover therefor, a downwardly extending plate beneath the cover having a flange secured thereto, said plate having upturned portions at its ends, 95 means pivotally connecting said upturned portions with said cowl, bearings formed upon said plate, a member having trunnions journaled in said bearings, and an operating rod for the cover having screw-threaded engagement with said member. 100
13. In an automobile body, a cowl having a ventilating opening, an instrument board, a cover for said opening, a plate rigidly secured to the cover and extending longitudinally thereof and downwardly and rearwardly beneath the same, means pivotally supporting the plate beneath the cowl, a member pivoted upon said plate, and an operating rod having its outer end extending through and guided by said instrument board and having its inner end threaded into 105 said pivoted member. 110

In testimony whereof, I affix my signature.

GEORGE E. GRIMM.
